ASSIGNORS, BY MESNE ASSIGNMENTS, TO UNITED SHOE MACHINERY COMPANY,
OF PATERSON, NEW JERSEY, A CORPORATION OF NEW JERSEY.

COMBINED SHOE-CUTTING PATTERN AND MARKER.

1,198,463.

Specification of Letters Patent. Patented Sept. 19, 1916.

Application filed May 18, 1914. Serial No. 839,441.

To all whom it may concern:

Be it known that we, RICHARD L. LLOYD and ROBERT D. SIMPSON, citizens of the United States, residing, respectively, at 5 Portsmouth and Columbus, in the counties, respectively, of Scioto and Franklin, State of Ohio, have invented certain new and useful Improvements in Combined Shoe-Cutting Patterns and Markers, of which the following is a specification.

This invention relates to combined patterns and markers for use in the shoemaking art and particularly applicable to marking and cutting by hand from sheet material the various parts of a shoe upper.

In the ordinary practice, the pattern outlining the shoe part to be cut from the upper material is placed on the sheet of upper material and a knife is drawn by hand around the edges of the pattern, cutting out the shoe part outlined by the pattern. Subsequently, the cut-out part is covered with a stencil plate and suitable indication marks placed thereon by punches 25 or by coloring matter suitably applied. In some instances, special machines, such as buttonhole marking machines, are employed to mark the parts. It will be evident, therefore, that two distinct operations have heretofore been necessary to cut out and mark the various parts of the shoe. These marks vary in character from the shape of the buttonhole, the point of attachment of the button, to indications for the junction of 35 parts. As this marking has been accomplished heretofore, the results have not been entirely satisfactory. When punches or prick awls have been employed, the material, particularly soft leather or cloth, 40 closes up after the mark has been made so that subsequently it is not discernible. The use of coloring matter is injurious to the leather as the liquid or paste will spread or smear. In the case of chalk, the mark 45 is easily rubbed off inadvertently or so blurred as to make it entirely ineffective.

Our invention provides a device which permits the cutting out of the pattern or shoe part from the material and the substantially simultaneous marking of the part. The marking medium employed is such that a dry indelible mark is made which does

not injure the shoe part and which is concealed or obliterated by the subsequent operations upon the shoe.

To this end, an important feature of our invention comprises a pattern having the outline of the shoe part to be cut out and provided with a series of heated cauterizing markers. As herein shown, the pattern 55 takes the form of a plate which may be superposed upon the shoe material with the markers in contact with the surface of the material, and, while a cutting knife is being drawn around its edges, the heated markers 60 are simultaneously cauterizing the surface of the material, providing a dry indelible mark which will not detract from the appearance of the shoe.

Another feature of our invention consists 70 in a pattern plate having electrically heated marking means on one face and provided with electrical connections for such marking means.

Another feature of the invention resides 75 in the novel manner of forming the marking members by the application of the electrical conductor to the body of the pattern plate. In the embodiment of the invention selected for illustration, this is accomplished by lacing an electric conductor through the pattern plate in such a manner 80 that marking portions of desired shape and configuration project from one face of the plate.

Another feature of the invention consists 85 in a structure providing different patterns on opposite faces, such as patterns in reverse duplicate for right and left hand parts, and separate electric heating connections for 90 each pattern. In addition, the arrangement of the electric connections is such that only one pattern may be heated for a single cutting and marking operation. Means are also preferably provided for insulating the 95 electric circuits of the two patterns from each other.

A further feature consists in a pattern plate having marking portions exposed on one face and arranged to be electrically heated to cauterize, with electric circuit connections to said markers on the opposite face of the plate arranged to remain comparatively cool during the passage of the

electric current therethrough. This feature is equally applicable to single and double pattern plates.

Still another feature of the invention consists in an indicator or tell-tale positioned for observation by the operator and designed to be heated similarly to the marking members so that the condition of the indicator is evidence of the condition of the markers.

Another and related feature of the invention is a switch or service connection for the heating circuits, which switch includes an exposed section of conductor similar to the heated marking portions and serving by its condition to indicate the condition of these marking portions.

Another feature resides in a service connection for the electric conductors of the heating circuit on the pattern plate, which makes connection with the pattern plate at the face opposite the marking portions.

A related feature is a construction of service connection providing an operating handle.

From the viewpoint of opposed patterns and markers, a further feature of the invention resides in a service connection for use with such a device which co-operates with the electric terminals of the heating circuits of the opposed patterns in such manner that only one pattern may be heated at one time.

These and other novel features of construction are more fully described in the following detailed specification and are illustrated in the accompanying drawings, in which—

Figure 1 is a plan view of the marking face of the lower plate of a reverse duplicate pattern embodying the present invention; Fig. 2 is a plan view of the bottom face of the top plate of such a pattern; Fig. 3 is a transverse section on the line 3—3 of Fig. 1; Fig. 4 illustrates the service connection or switch for the pattern heating circuits; and Fig. 5 is a detail of an electric connection.

In the accompanying drawing we have illustrated the pattern plate as designed particularly for use in forming and marking buttonhole flies inasmuch as this part of the shoe is one requiring a substantial amount of marking indications, but it will be understood that the invention is applicable generally to shoe patterns and is not limited to any particular form of pattern.

In the drawing, the superposed pattern plates 1 and 2 are reversely duplicate in outline, each outlining the buttonhole fly of a shoe. These plates are held in properly assembled relation by means of a metallic edging portion 3 extending about the peripheries of the plates and providing in addition a metallic guiding edge for the knife

of the operator. Each of these pattern plates is provided with a series of perforations 4 which are so arranged as to provide marking portions on one face of the pattern of the desired configuration. In case of patterns for buttonhole flies, they may be arranged in parallel pairs, as shown, or these pairs of perforations may radiate from the edge 5 of the pattern. As far as the present invention is concerned, the position of the perforations and their relative arrangement is entirely immaterial and will differ with the marking indication design. The perforations in the plates are designed to receive metallic eyelets 6 through which an electric wire 7 may be laced from the inner face of each plate, this wire passing from the inner face to the outer face through one aperture then transversely of the plate and to the inner face thereof through the adjacent aperture; thence lengthwise of the plate and to the outer face thereof through the next aperture and so on, as will be evident from Figs. 1 and 2 of the drawing. The exposed indication marking portions of the wire are indicated at 8, Figs. 1 and 3. The terminals of the heating circuit for the lower plate are indicated at 9, 10 and those for the upper plate are indicated at 11, 12 (Fig. 2). These terminals are preferably in the form of sockets to receive suitable service connections and are positioned at the opposite face of the plate from their exposed marking portions.

The service terminal connection is in effect a switch member and preferably takes the form of a handle 13 having projecting from its base service wire terminal plugs 14 arranged for insertion through perforations in opposite faces of the plates to connect with the terminal sockets 9, 10 and 11, 12. The service wires 15 and 16 lead from the service connection handle to suitable current connections. The body of the handle 13 is provided on one face with a cut-out portion 17 disclosing a portion of wire 18 forming an indicator or tell-tale section. This exposed wire portion is preferably of substantially the same heating capacity as the exposed marking portions 8 of the heating circuits so that the condition of the exposed indicator 18 is evidence of the condition of the marking portions 8 of the heating circuit wires on the opposite face of the pattern plate.

When the pattern is employed in a double one, as illustrated herein, a sheet 19 of suitable insulating material such as asbestos is preferably interposed between the adjacent inner faces of the connected plates, as best seen in Fig. 3 of the drawing.

It will be obvious that unless additional conductors are provided the portions of the wires 7 upon the inner faces of the plates will become heated to the same degree that

the exposed marking portions 8 are heated. To maintain the interior face of the heated plate in a comparatively cool state so that the plate may be handled by the operator, 5 metallic strips 20 are preferably formed integral with the eyelets 6 and are applied to the inner faces of the pattern plates so that the current will pass through the portions of the conductor upon the inner face of the 10 plate and also through these wire strips 20, distributing the current so that it can not possibly heat the inside face of the plate to any great degree. To obviate the necessity of providing a long strip for the return 15 portion of the conductor, the return portion of the wire may be made of a larger size, as indicated at 21, Figs. 1 and 2.

It will be evident that in the use of a pattern plate, such as is described, the service 20 connection 13 is applied to the plate at the face opposite that to be heated, its terminal 25 plugs 14 fitting in the terminal sockets of the heating circuit of the pattern plate to be heated and its indicator 18 informing the operator of the heated condition of the marking wires of the pattern plate. The operator places the pattern upon the shoe material at the desired point, drawing his knife around the edge to cut out the shoe part 30 while at the same time the heated marking portions of the wire are searing or cauterizing the surface of the material upon which they rest. Inasmuch as the terminals of the heating circuits are located at the faces of 35 the plates opposite the cauterizing wires, only one may be heated at a time, and, as is obvious, this heated plate is the one which is being used for cutting out the shoe part.

It will be understood that the structure 40 and use of the invention as recited herein is descriptive rather than definitive and that the structure and application of the device may be varied within the scope of the claims and the spirit of the invention. As an illustration, it is to be noted that the device of 45 the present invention is adapted also for use in marking corresponding shoe parts which have been previously cut out from sheet material by an agency other than the pattern plate and operator's knife, such, for instance, as shoe parts cut out by clicking machine dies.

Having particularly described our invention, what we claim as new and desire to secure by Letters Patent is:—

1. A shoe cutting pattern and marker comprising a pattern body having an electric wire laced therethrough so that it lies on both sides of said body, and supplemental 60 conductors in electrical connection with said wire on one side of said body to prevent that portion of the wire from heating when current is applied.

2. A shoe cutting pattern and marker 65 comprising a pattern body having an elec-

tric conductor laced through said body so that it lies on both sides of said body, said conductor being adapted to be heated by the passage of a current therethrough, and means for preventing heating those portions 70 of said conductor exposed on one of said sides.

3. A shoe cutting pattern and marker comprising two body members held clamped together, an electric wire laced through each 75 of said members and exposed at intervals on the outside faces of each member, and supplemental conductors in electrical connection with all of the portions of said wires lying against the inside faces of said members. 80

4. A shoe cutting pattern and marker comprising two body members held clamped together and each provided with a series of 85 perforations, eyelets for said perforations, metal strips electrically connecting each pair of eyelets on the inside faces of each body member, an electric wire laced through the eyelets of each member, said wires electrically engaging said metal strips on the inside face of said members, a strip of insulating material separating said two sets of wires, and two terminals in the outside face of each body member electrically connected 90 to their respective wires. 95

5. A shoe cutting pattern and marker comprising a pattern body structure having an electric wire laced therethrough in a manner that it is exposed at various portions to serve, when hot, for marking purposes, terminals in said plate for said wire, a switch member, and a wire forming a part of said switch member normally exposed to view and of approximately the same capacity as 100 said first named wire. 105

6. A plate having a continuous cutter-guiding edge permanently outlining a determinately shaped part to be cut out and having indication marking means on one face adapted to be heated to cauterize indication marks on the surface of shoe material. 110

7. A plate having a continuous cutter-guiding edge permanently outlining a determinately shaped part of a shoe to be cut out and having indication markers projecting from one face adapted to be heated to cauterize indication marks on the surface of the shoe material when resting thereon. 115

8. A plate having a continuous cutter-guiding edge permanently outlining a determinately shaped part of a shoe to be cut out and having indication markers on one face adapted to be electrically heated to cauterize indication marks on the surface of the material, and with electrical connections for the markers at the opposite face of the plate. 120 125

9. A plate having a continuous cutter-guiding edge permanently outlining a de- 130

terminately shaped part of a shoe and having indication marking means on one face adapted to be electrically heated to cauterize indication marks on the surface of the shoe material with electric service connections at the opposite face of the plate.

10. A pattern plate outlining a part of a shoe having an electrical conductor extended through from one face to expose portions on the other face of the plate of desired indication marking configuration arranged to be electrically heated to cauterize the surface of the shoe material.

11. A device providing for the cutting out of shoe parts of determinate outline from sheet material and the simultaneous placing of indication marks upon the surface of the material, comprising a plate provided with a continuous cutter-guiding edge having the permanent outline of a determinately shaped shoe part to be cut out, and having indication markers upon one face arranged to be heated to cauterize the surface of the shoe material.

12. A device providing for the cutting out of shoe parts from sheet material and the simultaneous placing of indication marks upon the surface of the parts comprising a pattern plate having the outline of a shoe part to be cut out and having an electrical conductor laced therethrough from one face to the opposite face in a manner to provide on the opposite face projecting portions of desired indication marking configuration arranged to be electrically heated to cauterize the surface of the shoe material.

13. A device providing for the cutting out of shoe parts from sheet material and the simultaneous placing of indication marks upon the surface of the parts so cut comprising a plate outlining the shoe part to be cut out and having an electric heating circuit providing exposed portions on one face of the plate of desired indication marking configuration and arranged to be electrically heated to cauterize the surface of the shoe material, the electric circuit connections for said exposed heating portions extending to the opposite face of the plate, and a service connection arranged for detachable connection with said heating circuit.

14. A pattern having cutter-guiding edges at its opposite faces outlining parts of a shoe to be cut out from sheet material, with separate electric heating circuits providing marking portions on opposite faces of the pattern of desired indication marking configuration, said marking portions being arranged, when electrically heated to cauterize the surface of the shoe material.

15. A pattern having cutter-guiding edges at its opposite faces outlining shoe parts to be cut out from sheet material, with separate electric heating circuits providing exposed portions on opposite faces of the pattern of

desired indication marking configuration adapted, when heated, to cauterize the surface of the shoe material, and with means for insulating said circuits from each other.

16. A device providing for the cutting out of different shoe parts from sheet material and the simultaneous placing of indication marks upon the surface of the parts, comprising superposed connected plates having cutter-guiding edges outlining parts of a shoe to be cut out from the sheet material, with separate electric heating circuits for each plate arranged to provide upon the opposite exterior faces of the plates indication marking means arranged to be electrically heated to cauterize the surface of the shoe material when placed thereon.

17. A device providing for the cutting out of different shoe parts from sheet material and the simultaneous placing of indication marks upon the surfaces of the parts comprising superposed connected plates having cutter-guiding edges outlining parts of a shoe to be cut out from the sheet material, with separate electric heating circuits for each plate arranged to provide upon the opposite exterior faces of the plates indication marking means arranged to be electrically heated to cauterize the surface of the shoe material when placed thereon, the terminals of said separate heating circuits being so arranged for service connections that only one heating circuit may be energized for a single cutting and marking operation.

18. A pattern having cutter-guiding edges at its opposite faces outlining parts of a shoe to be cut out from sheet material, with separate electric heating circuits providing exposed portions on opposite faces of the pattern of desired indication marking configuration, said exposed portions being arranged when electrically heated, to cauterize the surface of the shoe material, the terminals of said separate heating circuits being so arranged for service connections that only one heating circuit may be energized for a single cutting and marking operation.

19. A plate having cutter-guiding edges outlining a part of a shoe to be cut out from sheet material and having indication marking means on one face thereof arranged to be electrically heated to cauterize the surface of shoe material when placed thereon, with electric circuit connections for said marking means at the opposite face of the plate constructed and arranged to remain relatively cool during the passage of current through the circuit to heat the marking portion thereof.

20. A pattern plate outlining a part of a shoe and carrying an electric conductor positioned on both faces of the plate and arranged on one face of the plate to form indication markers of desired configuration arranged to be electrically heated to cauter-

ize the surface of shoe material when placed thereon, the conductor at the opposite face of the plate having increased conducting surface to prevent heat at the opposite face 5 of the plate.

21. A device providing for the cutting out of shoe parts from sheet material and the simultaneous placing of indication marks on the surface of the part comprising a plate 10 having the outline of a shoe part to be cut out and having indication marking means on one face thereof adapted to be electrically heated to cauterize the surface of the shoe material when placed thereon, and electric 15 circuit connections for the marking means at the opposite face of said plate including means to indicate the heat conditions of the marking means.

22. A device providing for the cutting out 20 of shoe parts from sheet material and the simultaneous placing of indication marks upon the surface of the part comprising a plate having the outline of a shoe part to be cut out and having indication marking 25 means on one face thereof adapted to be electrically heated to cauterize the surface of the shoe material when placed thereon, and electric service connections for said marking means at the opposite face of the 30 plate including an operating handle portion.

23. A device providing for the cutting out 35 of shoe parts from sheet material and the simultaneous placing of indication marks on the surface of the part comprising a plate having the outline of a shoe part to be cut out and having indication marking

means on one face thereof adapted to be electrically heated to cauterize the surface of the shoe material when placed thereon, and electric circuit connections for the marking means at the opposite face of said plate, including an exposed portion of conductor of substantially the same heating capacity as said marking means to indicate the heat condition of said means. 40

24. Means providing for the cutting out of reverse duplicate shoe parts from sheet material and the placing of indication marks on the surface of the parts simultaneously with the cutting out operation, comprising 50 two plates superposed upon each other and outlining in reverse duplicate shoe parts to be cut from said material, a metallic band extending around the cutting edges of the plates to join the plates and provide a 55 metallic guiding edge, separate electric circuits for each plate providing indication marking means on the exterior face of each plate arranged to be electrically heated to cauterize the surface of the material when 60 said face is placed on said material, means for insulating said separate circuits from each other, and service connections for the terminals of each circuit.
